RALPH C. CLARK, OF LOS ANGELES, CALIFORNIA, ASSIGNOR OF FORTY-NINE PER CENT
TO FRANK E. McCAGHEY, OF LOS ANGELES, CALIFORNIA

PISTON CONSTRUCTION

Application filed March 13, 1928. Serial No. 261,239.

The present invention relates to improvements in piston constructions and has reference more particularly to a piston for use in conjunction with mud or slush pumps.

5 One of the important objects of the present invention is to provide a piston that is of such construction as to render the same positive and efficient in carrying out the purposes for which it is designed.

10 Another important object of the invention is to provide a piston which is simple in construction, inexpensive, strong and durable, and further well adapted to the purpose for which it is designed.

15 Other objects of the invention will become apparent as the nature of the invention proceeds and when taken in connection with the accompanying drawings.

In the accompanying drawings, forming a part of this application, and in which like numerals designate like parts throughout the several views:

Figure 1 is an axial section of one form of the piston.

25 Figure 2 is a fragmentary side elevation of one end portion of the elongated hub or core showing the manner in which the complementary segments are associated with respect to each other, and further showing the operative association of the inner ends of the segments with the central radial flange formed on the hub or core.

30 Figure 3 is an end elevation thereof.

Figure 4 is a plan view of one of the segments.

Figure 5 is a similar view to Figure 1, showing another form of the piston.

Figure 6 is a vertical sectional view through the hub or core showing the spaced sockets formed in the radial flange and is associated with the hub and also disclosing in elevation, the slotted lateral web also carried by the hub.

45 Figure 7 is a view similar to Figures 1 and 5, showing a still further modification of the piston.

Figure 8 is a plan view of one of the segments forming a part of the piston construction disclosed in Figure 7.

50 Figure 9 is a detail view of the radial lugs

in associated relation with the type of hub disclosed in Figure 7 and showing the sockets formed in the respective lugs.

Figure 10 is an axial section through a modification of the hub or core and the complementary radially movable members associated therewith, and

Figure 11 is a fragmentary detail section showing the relation of one of the segments of the piston construction illustrated in Figure 5 and the adjacent web.

In the drawings, with reference more particularly to Figures 1 to 4 inclusive, the numeral 1 designates the elongated hub or core which is constructed of cast iron, the bore thereof being tapered gradually from one end to the other. This hub or core is adapted to be secured on a piston rod (not shown) in any appropriate manner for operation within a cylinder of a slush pump or the like. This hub or core is formed with a central relatively thick annular flange 2. This flange is formed in its opposite faces with a series of ball receiving sockets 3, the purpose of which will be presently described.

Forming a salient part of the present piston construction are the complementary triangular shaped segments 4, that are preferably constructed of bronze. Each segment is curved transversely and is formed at its inner end with a ball shaped head 5, for disposition within the respective sockets 3 provided therefor in the closed faces of the annular flanges 2, in the manner as clearly illustrated in Figures 1 and 2 of the drawings. Formed on the outer or larger end of each segment is the outwardly extending rim 6, the ends of which project beyond the respective sides of each segment and are furthermore cut away at diagonally opposite corners as indicated at 7.

The segments 4 are disposed around the hub or core 1 on opposite sides of the flange 2, so that the adjacent ends of the rims 6 will be disposed in overlapping relation as clearly shown in Figure 2, whereby to form a piston ring and the ball and socket connections provide a means whereby said segments are capable of radial swinging movement as will be presently described.

Rubber packing 8 is molded around the hub or core and the radially movable complementary segment 4 and loose packing completely encloses the central annular flange 2 and the major portions of the complementary segments. Substantially V-shaped channels 9 are formed in each end of the rubber packing 8 around the hub or core whereby to provide a means for the liquid 10 to enter the channels and expand the rubber packing and the segments 4 radially in outward directions against the inner wall of the cylinder.

With reference now to Figures 5, 6, and 15 11, wherein there is disclosed another form of the piston construction embodying my invention, the elongated hub or core is designated by the numeral 10 and formed at the central portion of the hub or core is the annular 20 flange 11 that is provided in one face with the socket 12 in the manner as more clearly illustrated in Figures 5 and 6 and for the purpose to be presently described. As clearly shown in the drawings, the sockets are 25 preferably located against the hub or core.

The hub or core 10 is furthermore formed with the radially disposed fan shaped webs 13, that are arranged on opposite sides of the central annular flange 11 and these fan 30 shaped webs are curved transversely. The webs are located in such a manner as to be disposed on opposite sides of the spaced sockets 12 and this construction is more clearly shown in Figure 6.

35 Forming a part of the piston construction disclosed in Figure 5 is a series of complementary segments such as are shown at 14, in Figure 4. Each of these segments is formed at its inner end with a ball shaped head 15 for cooperation with the respective sockets 12 provided therefor in the annular flange 11, while the outer or larger end portion of 40 each segment is formed with a rim 16, that is disposed naturally in an upward direction, and the ends of the rim are cut away at 45 diagonally opposed corners as illustrated at 17, whereby the adjacent ends of the sections and segment 14 will be disposed in overlapping relation when the segments are properly 50 assembled around the hub 10, so that a piston ring will be formed by the outer ends of the complementary segments.

The side edges of each segment are cut away as at 18, whereby to form a shoulder 55 19 and the shoulders cooperate with the curved faces of the arcuate webs 13, in the manner as clearly shown in Figure 11, so that said segments are capable of radial swinging movement by reason of the ball and socket 60 connection between the segments and the annular flange 11.

Rubber packing 20 is molded completely around the hub and the annular flange and arcuate web that extend from the outer face 65 of the intermediate portion of the hub or core

and furthermore, the rubber packing encloses the segmental sections and the piston rings formed by the outer ends thereof in the manner as clearly illustrated in Figure 5. The packing is, however, formed with the substantially V-shaped channels 21, in the respective ends around the hub, for the same purpose as the channels 9 formed in the rubber packing 8 molded around the hub 1.

In Figure 7, there is shown a further modification of the piston construction and in this instance the core or hub is designated by the numeral 22 and the bore thereof is tapered from end to end. A series of radially disposed lugs 23 are formed on the outer face of the hub 22 adjacent one end thereof and each of these lugs 23 is formed in its inner face with a socket 24, as more clearly disclosed in Figure 9. Radial webs 25 extend from the outer face of the hub 22 adjacent the other end thereof and as is clearly shown in Figure 7, the inner face of the web is slightly curved to permit the radial movement of the rib 26 that is formed transversely across the inner face of each of the triangular shaped segments 27, the outer face of the rib 26 being slightly convex to cooperate with the concaved face of the web 25.

The inner end of each of the triangular shaped segments is rounded to form a head 28, that is receivable in the respective socket 24 provided therefor in the adjacent lugs 23, whereby a pivotal connection for the inner end of each of the segmental sections is provided. A laterally disposed relatively wide rim 29 is formed at the outer larger end of each segmental section, and when the segments are arranged in assembled relation around the hub or core 22, the rim portions 29 of the segments will cooperate to form a 100 piston ring.

Rubber packing 30 is molded around the hub and the segments associated therewith and additional piston rings 31 are embedded in the end of the rubber packing remote from the piston ring formed by the complementary rims 29 of the segments 27. A V-shaped channel 32 is formed in each end of the rubber packing around the hub or core.

In Figure 10 of the drawings, there is shown a still further modification of the piston construction wherein the hub or core 33 is formed at one end with an annular flange 34, that is formed in its inner face with a series of sprockets 35, located adjacent the outer peripheral face of the hub or core. An annular flange 36 is formed on the other end of the hub or core 33 and the inner face of this flange is slightly concaved as illustrated at 37, for cooperation with the convex face of the rim portion 38, of each of the segments 39, the other end of each segment being formed with a ball shaped head 40 for cooperation with the respective socket 35, 115 120 125 130

whereby said segments are capable of radial swinging movement with respect to the hub. Rubber packing is adapted to be molded about the hub to completely enclose the segments.

5 It will thus be seen from the foregoing description that I have provided a piston construction that is more particularly adapted to be used in conjunction with mud or slush 10 pumps and due to its simplicity, the pistons can be readily and easily assembled and the ball and socket connections will permit radial expansion of the piston rings and the rubber packing so as to insure positive engagement 15 of the piston with the inner wall of the cylinder with which the piston is operable. Furthermore, the formation of the V-shaped channels in the ends of the rubber packing will afford a means whereby the liquid under 20 pressure will act to effect radial expansion.

A piston of the above mentioned character will be strong and durable and at the same time may be manufactured at a very low cost.

While I have shown the preferred embodiment of my invention, it is to be understood that minor changes in the size, shape and arrangement of parts may be resorted to, without departing from the spirit of the invention or the scope of the appended 30 claims.

Having thus described my invention, what I claim as new and desire to secure by Letters Patent, is:

1. In a piston, a hub, an annular flange 35 formed on the outer face of the hub, said flange being provided with spaced sockets in one face thereof, a series of complementary segments surrounding the hub, the inner ends of the segments being rounded for 40 disposition within the respective sockets whereby said segments are capable of radial swinging movement, and piston ring forming rims on the outer ends of the segments.

2. In a piston, a hub, an annular flange 45 formed on the outer face of the hub, said flange being provided with spaced sockets in one face thereof, a series of complementary segments surrounding the hub, the inner ends of the segments being rounded for disposition 50 within the respective sockets whereby said segments are capable of radial swinging movement, and piston ring forming rims on the outer ends of the segments, a rubber packing surrounding the hub and the segments, one end of said rubber packing being 55 formed with an annular channel for a purpose as described.

3. In a piston, an elongated hub, an annular flange formed on the outer peripheral 60 face of the hub and provided with a series of rounded sockets in one side face thereof, a plurality of segments surrounding the hub and disposed axially with respect thereto, the inner ends of the segments being rounded 65 for disposition in the respective sockets

whereby said sockets are capable of radial swinging movement, the outer ends of the segments being formed with laterally disposed rims, the rims of the complementary segments cooperating to form a piston ring, a rubber packing enclosing all of the aforesaid elements, the outer end of the rubber packing being formed with an annular channel that extends around the hub for the purpose described.

70 In testimony whereof I affix my signature.

RALPH C. CLARK.
